UNITED STATES PATENT OFFICE.

HARRY C. DECK AND GEORGE FULTON, OF ROODHOUSE, ILLINOIS.

KNOCKDOWN CRATE.

No. 801,183.

Specification of Letters Patent.

Patented Oct. 3, 1905.

Application filed September 26, 1904. Serial No. 226,037.

To all whom it may concern:

Be it known that we, HARRY C. DECK and GEORGE FULTON, citizens of the United States, residing at Roodhouse, in the county of Greene and State of Illinois, have invented 5 certain new and useful Improvements in Knockdown Crates; and we do declare the following to be a full, clear, and exact description of the invention, such as will enable 10 others skilled in the art to which it appertains to make and use the same.

Our invention is an improved knockdown structure adapted to be used as a crate, shipping-case, and for other purposes; and it 15 consists in the construction, combination, and arrangement of devices hereinafter described and claimed.

In the accompanying drawings, Figure 1 is a perspective view of a crate embodying our 20 improvements. Fig. 2 is a vertical longitudinal sectional view of the same, showing it folded in dotted lines; and Fig. 3 is a vertical transverse sectional view of the same.

The bottom 1 of the crate or casing is here 25 shown as solid or imperforate. It may be of any suitable construction. On the upper side of the bottom 1 near its ends are transverse cleats 2. The sides 3 of the case or crate are here shown as composed of a plurality of slats 4 and cross-bars 5, which connect them together at their ends and at their centers and are secured to the inner sides of the said slats. The sides 3 are secured to the inner sides of the bottom by means of hinges 30 6, which permit the said sides to be folded over on the bottom, the width of the latter being such as to enable both of the sides to be folded thereon without overlapping each other. The top of the case or crate is composed 35 of a pair of sections 7, each of which comprises a plurality of slats 8 and a plurality of spaced cross-bars 9, which connect them together. The said top sections are respectively connected to the sides 3 by means of hinges 9^a, 40 which are here shown as strap-hinges having their members which are secured to the sides of open construction, so as to afford ventilation through the sides and offer a minimum obstruction to the ventilating openings 45 50 formed in the sides by the spaces between the slats and cross-bars of which they are composed. The top sections are adapted by the hinges 9^a to fold outwardly over the said sections, as shown in dotted lines in Fig. 3. The 55 ends of the slats or bars 8 of the top sections project beyond the ends of said sections for a

slight distance, as shown. The ends 10 of the crate or case are also of open construction and are composed of slats 11 and connecting cross-bars 12. The said ends are 60 adapted to fit on the bottom against the outer sides of the cleats 2 and between the sides and the top sections, and the upper slats of the ends are provided with openings 13 to receive the projecting ends of the slats 65 of the top sections to lock the top sections in a closed position when the ends are closed. The ends are connected to the bottom by means of hinges 14, which are identical in construction with the hinges 9^a, hereinbefore 70 described. In the sides of the ends are notches 15 to clear the projecting eye portions 16 of keepers 17, which are secured to the inner sides of the sides 3 and which adapt the ends when closed to be secured by seals 75 such as are used on the doors of freight-cars. The ends are adapted by their hinges 14 to be folded under the bottom of the case or crate, as shown in dotted lines in Fig. 2.

When the casing or crate is set up, the top 80 sections bear on the upper ends of the cross-bars 5, which form projections on the inner side of the side sections and also bear on the upper end of the cross-bars 12, which form projections on the inner sides of the end sections. 85

It will be understood that our improved case or crate may be readily set up, may be used for shipping poultry and for goods and commodities of various kinds, and that when 90 emptied and knocked down it is very compactly disposed and will occupy but little space.

From the foregoing description, taken in connection with the accompanying drawings, 95 the construction and operation of the invention will be readily understood without requiring a more extended explanation.

Various changes in the form, proportion, and the minor details of construction may be 100 resorted to without departing from the principle or sacrificing any of the advantages of this invention.

Having thus described our invention, what we claim as new, and desire to secure by Letters Patent, is—

A structure of the class described comprising a bottom, end sections hinged thereto, adapted to be folded under the bottom and having projections on their sides, side sections hinged to the bottom, adapted to be folded over the same without overlapping 110

and having projections on their inner sides, and top sections hinged to the side sections, adapted to be folded outwardly over the side sections when the structure is folded and to 5 bear on the projections of the side and end sections when the structure is set up, said ends having recesses to receive the ends of the top sections and being further provided with notches, the said sections having keepers 10 at their ends to enter and project through

the notches in the end sections of the structure.

In testimony whereof we have hereunto set our hands in presence of two subscribing witnesses.

HARRY C. DECK.
GEORGE FULTON.
